ELEVATOR CONTROL SYSTEM

William F. Eames, Edgewood, Pa., assignor to
Westinghouse Electric Elevator Company, Jersey
City, N. J., a corporation of Illinois

Application March 30, 1938, Serial No. 198,881

10 Claims. (Cl. 187—29)

My invention relates to elevator control systems and more particularly to systems where an elevator serves a large number of floors with a high maximum car speed and where the car automatically slows down in response to operated push buttons at the floors or in the car.

It is an object of my invention to use the highest possible car speed in making any run between floors and to have the car slow down and stop at any predetermined floor in the shortest distance possible consistent with passenger comfort.

Where the distance between floors that is to be traversed by the elevator is too short to permit the highest car speed to be used, it is an object of my invention to provide a mechanism that will cause the car to accelerate for approximately half the distance at the maximum rate of acceleration that the comfort of the passengers will permit and to retard the car during the remaining distance also at the maximum rate their comfort will permit.

It is an object of my invention to provide a mechanism that will automatically select the correct point in car travel of any number of floors for the transition from acceleration to retardation to occur, in the event that the car does not reach its maximum speed. In the event that maximum speed is reached, the mechanism will select the correct point of car travel for retardation to start so that the car will slow down at a comfortable maximum rate of retardation and stop level with the desired floor.

It is an object of my invention to provide a mechanism that will automatically select the maximum speed that can be used in any given run in advance of the car attaining that speed such that the desired rates of acceleration and retardation will be utilized in making the run.

It is, therefore, an object of my invention to provide a mechanism operable in accordance with the distance the car must move for determining the maximum speed it may attain.

Another object is to provide a mechanism operable in accordance with the position of the car cooperating with the distance responsive element for determining the point at which retardation must start.

A still further object is to provide a mechanism that will cause the elevator car to accelerate in a plurality of steps at a predetermined rate and to retard in a plurality of steps at a different predetermined rate.

Other novel features of my invention will be

come apparent from the following description of the drawings and the operation.

An embodiment of my invention is illustrated in the accompanying drawings.

Figure 1 shows a view of a car in a shaftway with accessories on the car and in the shaft which are desirable for this particular embodiment.

Fig. 2 is a detailed view of a floor selector used in addition to the equipment shown in Fig. 1.

Figs. 3 and 4 show diagrammatic arrangements of the circuits to the equipment of Figures 1 and 2. To make it easy to follow the circuits, they are shown in straight line form in which contacts are not shown associated with their operating coils and selector parts are shown in various places but without regard to their actual physical arrangement as shown in Fig. 2.

Figs. 3A and 4A show the physical relation between the contacts of Figs. 3 and 4 and their operating coils. Figs. 3A and 4A also form a key to the location of the parts of Figs. 3 and 4. If the latter are laid beside the former horizontal lines across the diagrams in connection with the vertical lines of the former will locate approximately in the diagrams the contacts that any given coil operates as well as locating the coils.

A more detailed description of the apparatus of the figures will be found desirable in understanding the invention. Referring again to Fig. 1 an elevator car 10 is moved up and down its shaft by the traction between the supporting cables 11 and a driving sheave 12. A motor 13 drives sheave 12 and the sheave may be held stationary by a brake 14 which is released by magnet 15 when the car is to be moved. Counterweights 16 on the other end of cable 11 balance the car and part of its load and help to provide traction. The car is illustrated as operating past a plurality of floors of which 1 to 5 inclusive are illustrated.

Associated with each intermediate floor are plates that cooperate with two switches IE and IF carried by the car. Thus the second floor has associated with it plates 2a and 2b that cooperate with switch IF and plates 2c and 2d that cooperate with switch IE. These plates are mounted in the hatchway in such a manner that when switch IF passes plate 2b with coil F energized that contact F1 is opened until the switch is moved out of range of the plate. Similarly, contact F2 is opened by plate 2a and when coil E is energized, contact E1 is opened by plate 2d and contact E2 is opened by plate 2c. This same action occurs at the plates associated with the other floors.

40

35

45

50

55

Plates 2c and 2d are stationed at a point approximately midway between floors 1 and 2. The end of plates 2c that extends towards floor 2 is located at the distance from floor 2 at which it is desired to have the retardation begin such that a correct stop at floor 2 will result when the car is moving at the speed used for one floor runs. The end of plate 2d towards floor 1 is similarly located with reference to the first floor. The 10 plates are long enough to overlap in position with their opposite ends.

Plates 2a and 2b are located approximately at floor level at floor 2. The lower end of plate 2a is located a few inches below floor 2 at a point 15 where it is desired to set the car brake so that the car will stop from its slowest speed just level with the floor when travelling in the up direction. The upper end of plate 2b is located a few inches above floor 2 at a point where it is desired to set 20 the brake when the car is travelling downward at its slowest speed so that the car will just stop level with the floor.

Other plates for other floors such as 3a, b, c, and d and 4a, b, c, and d are similarly located. 25 These positions are based on the assumption that the switches IE and IF are at the car floor level. It is usually desired to mount these switches on top of the car approximately 8 feet higher. To maintain the relationship of the plates correctly, 30 all plates should then be moved up 8 feet higher in the shaft.

Other auxiliary apparatus shown in the view of the car is as follows. A master switch 40 may be used to start the car up or down. A position 35 indicator 17 shows the car's location or potential location, as will be explained later. This indicator is illustrated as having a series of lights one for each floor. When the car is stopped at a floor, the appropriate light is illuminated. Other forms 40 of indicator are also suitable. An auxiliary signal 18 is provided to indicate when the selector mechanism is in synchronism with the car's position. Three push buttons 19-20 and 21 are provided to resynchronize the selector if it should 45 get out as will be explained later. Car push buttons are provided in a panel 22 for setting up floor stops from within the car. There is one button for each floor served. Button 2CB is provided for the second floor and similarly identified buttons are provided for other floors. 50

A plurality of floor push buttons 5FB to 1FB are illustrated. To avoid unnecessary complication of the circuits of the diagram, only a single button is shown at each intermediate floor. It 55 is well known in the art how to provide an up and a down button at intermediate floors and how to connect them so that the up button functions only during up travel and the down button only on down travel. The description of the 60 operation will, therefore, be confined to up motion. It will be found that the system shown will function correctly for down motion if the floor buttons are pressed when the car is above the floor.

Fig. 2 shows a side elevation of a floor selector 65 that may be used in my invention. Other types of selectors may be used with this system. The principles of operation are illustrated in this figure as follows. A motor 23 runs continuously 70 and drives through a series of shafts and speed reducing gearing 24a and 24b two splined shafts 25a and 25b. Loosely mounted on these shafts are clutch face plates of magnetic material 26a and 26b. In line with shafts 25a and 25b are two 75 shafts 28a and 28b supported in bearings 30a and

30b rotating sheaves 31a and 31b. Loosely supported on shafts 28a and 28b are two coils 27a and 27b. These coils are stationary but the shafts and magnetic structures forming part of the shafts are free to rotate. If desirable, the coil 8 may rotate and energizing connections may be brought into the coil through slip rings (not shown) as is well known in the art.

When the coils 27a and 27b are energized, magnetic attraction pulls the clutch faces 26a and 26b in contact with friction surfaces 29a and 29b which are fastened to shafts 28a and 28b. The friction developed due to the pressure of faces 26a and 26b on surfaces 29a and 29b caused by the magnetic flux set up by coils 27a and 27b 15 is sufficient to rotate shafts 28a and 28b and therefore sheaves 31a and 31b in synchronism with continuously rotated shafts 25a and 25b.

Contact fingers 32a and 32b are fastened to shafts 28a and 28b and connect conductor rings 20 33a and 34a also 33b and 34b. These rings are divided into segments so that circuits are made and broken by contact fingers 32a and 32b as they rotate as will be explained more in detail 25 later.

Part of shafts 25a, 25b, 28a and 28b are shown in cross section. Also clutch faces 26a and 26b, coils 27a and 27b, friction faces 29a and 29b, contact fingers 32a and 32b, conductor rings 33a, 33b, 34a, and 34b are shown in section for clearness.

A cable 35 passes over sheave 31a down behind a selector panel 36 under an idler sheave 31a and the two ends of cable 35 fasten to a cross arm 41. Cable 35 is held in tension to provide traction on sheave 31a by a spring 39a that pulls on a bearing support 38a.

A second cable 42 passes over sheave 31b, down behind panel 36, under a sheave 31b and the two ends fasten to a switch operator 43. Cable 42 40 is held in tension by members similar to those for cable 35.

Switch operator 43 is of such size that if it passes between a stationary member 44 and a movable member 45 that a switch blade 46 is 45 moved in contact with switch stud 47 against the biasing action of a spring 48 thereby closing any circuit that may be connected to blade 46 and stud 47.

Selector cross arm 41 is arranged to move up 50 and down across the face of panel 36. A plurality of brushes 60-70-80-90 carried by arm 41 make circuit successively with a plurality of conducting segments 61-62, etc., mounted on panel 36. Five horizontal rows of segments are illustrated representing four circuits closed by the brushes corresponding to five floors served by the elevator. The functions of these circuits and that of switch members 46 and 47 will be explained later. Flexible conducting cables 53 serve 60 to carry electrical conductors from the cross arm 41 to stationary parts of the selector that may in turn be connected to other apparatus.

Fig. 3 shows the connections for the various 65 pieces of apparatus. Motor 13 has its armature 13a connected in loop circuit with an armature 54c of a variable voltage generator in the well known Ward-Leonard connection. Motor 13 has its shunt field 13b continuously energized from 70 two supply lines L1 and L2. Electromechanical brake 15 has its coils energized through the contacts M1 of a switch M. Generator 54 is supplied with two fields the first a shunt field 54a energized by either of two reversing switches U or D 75.

and the second a series field 54b energized by the current flowing in the loop circuit.

Master switch 40 when moved to the left starts the car up by energizing coils U and M, as will be explained later. Similarly, moving it to the right starts the car down. A series of lamps 5PI to 1PI are those which give car position indications by illuminating indicator 17 in the car. Floor push buttons 5FB to 1FB are shown connected to a plurality of call storing relays 5R to 1R. Each relay is provided with cancelling coils 5RN to 1RN. When both the pick up coil and cancelling coil for these relays are energized at the same time, they oppose each other and the relay armature drops to the deenergized position.

Car push buttons 5CB to 1CB are shown connected to selector segments 85 to 81. Each button is provided with a holding coil 5CBH to 1CBH. Each coil while energized is not strong enough to move the button plunger, but if the plunger is pressed in manually, the coil is sufficiently strong to hold it in the depressed position until the coil is deenergized.

Referring to Fig. 4, the circuits shown are a continuation of those of Fig. 3 and the operation of them will best be explained by assumed operations. The various switches and relays of Figs. 3 and 4 are designated by the identifications listed in the following table and opposite each is given a brief description of the function of the relay or switch in the circuits.

1A	Selector start relay
2A	Auxiliary selector start relay
1B	Selector drive interlocking relay
2B	Auxiliary selector interlock relay
1C	Selector stop relay
2C	Auxiliary selector stop relay
D	Down direction switch
DR	Auxiliary down relay
E	Intermediate inductor
F	Stop inductor
G to 6G	Speed relays
H	Door and gate switch
I	Inductor interlocking relay
M	Brake switch
O	Auxiliary stopping relay
IP	Call pick up relay
2P	Car call pick up relay
1Q	Acceleration timing relay
2Q	Acceleration timing relay
1R to 5R	Floor call storage relays
SR	Retard relay
U	Up direction switch
UR	Auxiliary up relay
W	Up direction preference
X	Down direction preference
1Y	Chain operating relay
2Y	Chain operating relay

The general operation is as follows, assuming the car at the first floor and a call at the fourth floor: When the doors are closed, and the master switch moved to start the car upward, the speed relays will come in rapid succession until the speed switch is energized that corresponds to the maximum speed the car can obtain during acceleration and still stop at the fourth floor with normal retardation. As the speed relays come in the selector moves forward and when the selector reaches the fourth floor, it will stop and no more speed switches will come in. The car may have moved half a floor during this action. Acceleration will continue as the generator field builds up and as the car moves forward until it reaches a point about midway between the first

and fourth floor or half way between the second and third floors. When the car reaches this point, the auxiliary selector will have moved to the fourth floor position and retardation starts. The car then proceeds to the 4th floor retarding continually and finally stops there. The selectors do not move during the retardation operation.

If the call had been at the fifth floor more speed switches would have been energized and if at the third fewer. The selector motions would have been similar but the point of stopping would have been the fifth floor position in the first and the third floor in the second.

If the call was placed sufficiently far in advance of the car's position, the car will accelerate to its full speed, run at this speed to the point at which slow down must start, then retard during the remaining travel until it stops at the floor where the call is registered. In the embodiment of the invention being described, to answer a call at the 9th floor the car will leave the first floor, will accelerate approximately during 3 floors travel, will run at full speed for approximately 2 floors travel and will retard for three floors travel to respond to a call placed at the 9th floor (not shown) any time prior to the car reaching the 6th floor position. A speed of 1200 feet per minute can be easily obtained in this run without producing discomfort to passengers in the car. All stops are positive and any intervening stop can be made with the desired sequence of the controller provided only that the call is registered before the car reaches the point where slow down must start to make the desired stop.

As the invention may best be understood from a description of an operation, it will be assumed in the following description that the car is standing at the first floor, that a call is placed at the 4th floor, and that the car is started upward to respond to any call that may be registered. The action of the controller will be as follows.

First floor to fourth floor run

When the car is standing at the first floor in readiness to run, switch coil W will be energized (limit switch 55 being opened by the car standing at the first floor)

L1—D4—X1—W—5G—L2 (Fig. 3)

(The circuit may be traced through the elements on the diagram bearing the numbers in the sequence).

When the car is at the first floor in readiness to make a run switch operator 43 on the selector will be positioned opposite stationary member 44 of cross arm 41. In this position switch blade 46 will be in contact with switch stud 47 and signal light 18 on the car will be illuminated.

L—47—46—18—L2 (Fig. 4)

The illumination of this lamp indicates to the operator that the selector parts are properly positioned as it should normally be illuminated when the car is at rest. Its use will be explained later.

Relays 1Y and O will be energized.

L1—2Y3—1C3—1P7—SR5—2Y2—1Y—L2 (Fig. 4)
L1—1G5—2G3—3G2—4G2—5G2—6G4—O—L2 (Fig. 4)

Inductor coils E and F are energized continuously.

L1—E—F—L2 (Fig. 4)

When the car is standing at the first floor, inductor plates 1b and 1a will be positioned in inductor IF, and contact members F1 and F2 will be moved to circuit opening positions under the influence of energized coil F. As no plates are positioned in inductor IF at this time its contact members E1 and E2 will close their respective circuits. No action will result from these closed members as their circuit is opened by relay contacts UR2 and DR2 (Fig. 4).

If we assume a call now placed at the 4th floor by pressing push button 4FB then relay 4R will be energized.

15 L1—4FB—4R—L2 (Fig. 3)

and when pressure is released on push button 4FB relay 4R will remain energized.

16 L1—4R—4R—L2 (Fig. 3)

20 The closing of contact 4R2 connects selector segment 94 (Fig. 4) to supply wire L2 but no action results at this time.

25 The car is now started upward. In the embodiment of my invention illustrated in the drawings, this starting is accomplished by closing the elevator door and the car gate, and by moving car starting switch 40 to the left. Any of the well known methods of starting the car may be used, or the car may be started automatically in response to the operation of push button 4FB in a manner well known in the art.

30 When the door and car gate are closed a circuit is closed by interlocks on these members to energize a coil H (Fig. 3). Contact H2 energizes the coil of relay G

35 L1—H2—M7—G—L2 (Fig. 4)

Contact G2 energizes coil 1G

40 L1—H2—1Y2—1P0—G2—1G—L2 (Fig. 4)

45 Contact 1G5 opens the previously traced circuit to coil O and this relay drops to the deenergized position preparing the car starting circuits for starting. No further action results at this time.

50 When car starting lever 40 is moved a circuit is established to energize coils U and M.

55 L1—40—U—M—H1—L2 (Fig. 3)

Contact M7 opens the previously traced circuit to coil G but this coil is now held energized by a holding circuit.

60 L1—H2—2Y6—G1—G—L2 (Fig. 4)

Contact M5 energizes coil 1Q

65 L1—M5—6G2—1P3—2Q1—1Q—L2 (Fig. 4)

60 Contact 1Q1 energizes coil 2Q

70 L1—M5—6G2—1P3—1Q1—2Q—L2 (Fig. 4)

75 Relay 2Q, in picking up, opens contact 2Q1 which breaks the previously traced circuit to coil 1Q. The armature of relay 1Q does not drop immediately to the deenergized position however, as it is delayed by a time element as indicated in Fig. 4A. Relay 2Q in picking up closes contact 2Q2 which energizes coil 1A.

L1—1A—2Q2—L2 (Fig. 4)

Contact 1A1 energizes clutch coil 27a

75 L1—1A1—1C2—27a—L2 (Fig. 4)

The energizing of coil 27a causes engagement of clutch parts 26a and 29a, driving cable 35 and moving cross arm 41 towards the row of segments corresponding to the second floor (62—72—82—92).

As clutch coil 27b has not been energized, cable 42 and operator 43 do not move, and the motion of the cross arm moves switch member 45 out of engagement with operator 43. As a result switch contact 46—47 opens the circuit previously traced, 10 and lamp 18 on the car is extinguished.

As shaft 28a turns, contact finger 32a moves with it, first breaking the circuit between contact segments 33a and 34a, and then making a circuit between contact segments 33c and 34c (Fig. 15 4). Contact segments 33c and 34c energize coil 1B.

L1—33c—32a—34c—1B—2Q2—L2 (Fig. 4)

20 Next relay 1Q expends its time element and drops to the deenergized position and contact 1Q1 interrupts the circuit to coil 2Q previously traced. The armature of relay 2Q is delayed in moving to the deenergized position by a time delay as indicated in Fig. 4a.

25 Shaft 28a continues to rotate and arm 32a moves out of contact with segment 33c and 34c and into contact with 33a and 34a. The circuit to coil 1B remains energized through its holding contact 1B2 and coil 1C becomes energized.

30 L1—33a—32a—34a—1B—1C—L2 (Fig. 4)

35 Contact 1C2 deenergizes clutch coil 27a by opening the previously traced circuit to it. The clutch parts move to the unoperated position and cross arm 41 stops in such a position that the moving brushes 60—70—80—90 engage segments 62—72—82—92 respectively.

40 Contact 1C3 opens the short circuit around coil 2Y and this coil becomes energized.

L1—2Y—1Y1—1Y—L2 (Fig. 4)

Contact 2Y5 closes an additional circuit to coil 1G

45 L1—H2—2Y5—1G3—1G—L2 (Fig. 4)

50 Contact 2Y6 opens the previously traced holding circuit to coil G and this relay drops to the deenergized position. Contact G2 opens the previously traced pick up circuit for coil 1G but this relay holds in through the circuit closed by contact 2Y5.

55 While considerable space is required to describe all the foregoing control action, it takes place rapidly and between a half second and one second time is required. During this time voltage is building up on the generator from the energization of its field 54a through circuit.

60 L1—U1—54a—U2—58a—58b—58c—58d—58e—1G1—L2 (Fig. 3)

65 The elevator motor brake coil 15 has been energized.

L1—15—M1—L2 (Fig. 3)

70 Current circulates in the loop armature circuit.

75 54—54b—13a—54 (Fig. 3)

80 and the elevator motor 13a starts to turn moving 70 the elevator in the up direction.

85 As the car moves inductor plate 1b leaves inductor IF, inductor contact F1 closes, to energize coil DR

L1—DR—F1—L2 (Fig. 4)

Further movement of the car causes plate **1a** to leave the inductor and contact **F2** to close energizing relay **UR**.

L1—UR—F2—L2 (Fig. 4)

5 Contact **UR2** energizes relay coil **I**

L1—I—UR2—DR2—E1—E2—L2 (Fig. 4)

Contact **I1** energizes coil **2A**.

10 **L1—2A—SR3 and IP5 (in parallel)**

I1—L2 (Fig. 4)

Contact **2A1** energizes clutch coil **27b**.

L1—2A1—2C3—27b—L2 (Fig. 4)

15 which engages clutch surfaces **26b** and **29b** which causes shaft **28b** to turn sheave **31b**, moving switch operator **43** towards the second floor position now occupied by switch members **44—45—46—47** on cross arm **41**.

20 We will now assume that the time element for the armature of relay **2Q** expires and the armature drops to the deenergized position. Contact **2Q1** again establishes a circuit to energize coil **1Q**.

25 **L1—M5—6G2—IP3—2Q1—IQ—L2** (Fig. 4)

Contact **2Q2** opens the previously traced circuit to coils **1A** and **1B**. Contact **1B1** opens the previously traced circuit to coil **1C**. Contact **1C3** in closing shorts coil **1Y**.

Coil **1Y—1Y1—2Y1—SR5—IP7—**

1C3—2Y4—L2—coil 1Y (Fig. 4)

30 Relay **1Y** drops to the deenergized position opening contact **1Y1** but relay **2Y** remains energized.

L1—2Y—2Y1—SR5—IP7—

1C3—2Y4—L2 (Fig. 4)

Contact **1Y3** energizes coil **2G**

40 **L1—H2—1Y3—IP10—1G4—2G—L2** (Fig. 4)

Contact **2G1** shorts out an additional section of generator field resistance **58e** which increases the voltage of generator armature **54** and raises the speed of motor **13a** (Fig. 3).

45 While this sequence was occurring after contact **2Q1** again energized the coil of relay **1Q** another sequence was progressing.

Contact **1Q1** again energized coil **2Q** by a circuit previously traced. Contact **2Q1** deenergizes coil **1Q** which will drop after a time delay. In the meantime contact **2Q2** energizes coil **1A** which energizes clutch **27a**. Relays **1B** and **1C** again pick up to deenergize clutch coil **27a** and the selector cross arm **41** is moved again this time to the third floor position.

50 Contact **1C3** in opening breaks the previously traced holding circuit to coil **2Y**, and **2Y** moves to the deenergized position. Contact **2Y5** breaks the previously traced holding circuit to coil **1G**, and this relay drops to the deenergized position.

55 Clutch coil **27b** was previously energized and its shaft started turning to move switch operator **43**. As the shaft turns contact finger **32b** is moved to connect segments **33d** and **34d** of the commutator ring associated with contact finger **32b** to energize coil **2B**.

60 **L1—33d—32b—34d—2B—SR3 and IP5 (in parallel)—I1—L2** (Fig. 4)

70 Relay **2B** establishes a holding circuit through contact **2B1**. As the selector shaft **28b** turns contact finger **32b** again connects segments **33b** and **34b** picking up coil **2C**.

75 **L1—33b—32b—34b—2B1—2C—L2**

Contact **2C3** opens to deenergize clutch coil **27b** stopping further motion of switch operator **43** which is now stopped at a position corresponding to the second floor.

At this time cross arm **41** is in the third floor position, switch operator **43** in the second floor position the car is just leaving the first floor. Speed controlling contact **2G1** is closed shorting resistors sufficient to bring the car to a speed suitable for a two floor run. As no call exists at the third floor the action continues.

80 Relay **1Q** time element now expires and its armature drops to the deenergized position. Contact **1Q1** opens the circuit to coil **2Q** which also after a time delay drops to the deenergized position. Contact **2Q1** immediately reenergizes coil **1Q** and contact **2Q2** deenergizes coils **1A** and **1B**. Contact **1B1** deenergizes coil **1C**. Contact **1C3** in closing energizes coil **1Y**.

L1—2Y3—1C3—IP7—SR5—2Y2—IY—L2 20
(Fig. 4)

Contact **1Y2** energizes coil **3G**.

L1—H2—IY2—IP8—2G5—3G—L2 (Fig. 4)

25 Contact **3G1** (Fig. 3) shorts an addition section of generator field resistor, **58d** further increasing the generator field and motor speed to a value suitable for a three floor run.

In response to the energizing of coil **1Q** for the third time, contact **1Q1** again energizes coil **2Q**, contact **2Q1** again deenergizes coil **1Q** to cause it to drop after a time delay. Contact **2Q2** again energizes coil **1A**, and contact **1A1** energizes clutch coil **27a** for the third time and cross arm **41** is again moved forward, this time, to the 4th floor position.

30 When relay **1C** picks up for the third time, contact **1C2** deenergizes clutch coil **27a** which as before stops the motion of the cross arm. Contact **1C3** opens the short on coil **2Y** which picks up as before. Contact **2Y6** opens a holding circuit to coil **2G** which may be traced as follows.

L1—H2—2Y6—2G4—2G—L2 (Fig. 4) 45

35 When cross arm **41** moved to the 4th floor position moving contact **90** engaged segment **94** (Fig. 4). Contact **4R2** previously connected this segment to **L2**, contact **2C4** was previously closed by coil **2C** being energized so that contact **1C4** now closing completes a circuit for energizing coil **1P**.

L1—IP—1C4—2C4—90—94—4R2—L2 (Fig. 4)

40 Contact **1P1** establishes a self-holding circuit 55 for coil **1P**.

L1—IP—1P1—M8—L2 (Fig. 4)

Cross arm **41** moves brush **70** into contact with segment **74** and the closing of contact **1P1** energizes the circuit for coil **4RN**

L1—4R1—4RN—74—70—1P1—L2 (Fig. 3)

45 This coil opposes the previously energized coil **4R** so that relay **4R** drops to the deenergized position and contact **4R1** opens the circuit to both coils. Contact **1P3** opens, and prevents further action from relays **1Q** and **2Q**.

50 Cross arm **41** moves brush **60** successively in contact with segments **62**, **63** and **64** lighting each **70** associated position indicator light. While the car is at this time positioned between the first and second floors, the indicator will show it as at the fourth floor position. That the car is at the fourth floor position is true in the fact that 75

circuits are set up for the stopping at the fourth floor such that the car cannot make a normal stop at a floor nearer the car's position than the fourth floor. To avoid confusion as to when the car is actually positioned at the fourth floor and when it is potentially positioned there, a signal modifying device 57 is provided which causes the indicator signal to flicker on and off until the car actually arrives. Since contacts M4 and 10 IP2 are both open, current to lamp 4PI is intermittently interrupted in its passage through flicker device 57. When the car finally comes to rest at the fourth floor, contact M4 closes and lamp 4PI burns steady indicating that the car has arrived.

Up to this point, we have the car accelerating away from the first floor or an uptrip. The following relays and contactors are energized, W, H, U, M, 1Y, 2Y, 3G, 1P, DR, UR, I, 2A, 2B and 2C. The selector cross arm has moved ahead to the 4th floor position where a call has been registered. The call has been cancelled. The switch operator 43 of the selector has advanced to the second floor position.

As the car progresses upward, plate 2d enters inductor IE opening contact EI without effecting action. The car at this time is about midway between the first and second floor accelerating to a speed suitable for a 3 floor run. Plate 30 2c now enters inductor IE opening contact E2 which interrupts the circuit to coil I.

Contact 1I interrupts the circuit to coils 2A and 2B and contact 2B1 interrupts the circuit to coil 2C. These three relays drop to the de-energized position, preparatory to the next operation of selector switch operator clutch 27b.

With further movement of the car plate 2d leaves the inductor and contact EI closes and after a few more inches of travel plate 2c leaves 40 closing contact E2 to reenergize relay I.

The circuits to relays 2A, 2B, 2C and clutch 27b are reenergized in the sequence previously described to cause switch operator 43 to move to the third floor position.

45 As the car passes the second floor, plate 2b enters inductor IF opening contact F1 dropping relays DR—I—2A—2B and 2C in sequence to again reset the circuit for further operation. Plate 2a opens contact F2 deenergizing relay UR without effect. Plate 2b leaves closing contact F1 picking up relay DR without effect. Finally plate 2a leaves closing contact F2 picking up relays UR—I—2A—2B—2C as previously described and energizing clutch 27b for the third 55 time and switch operator 43 is moved to the 4th floor position, or the position to which the selector cross arm was moved by the repeated actuations of relay 2Q. When relay 1P became energized further actuation of relay 2Q was prevented by contact 1P3 opening.

As the switch operator 43 is moving into its final position at the fourth floor position on the selector, switch members 46 and 47 close.

Relay 2C then is picked up by finger 32b to 65 stop the motion of switch operator 43 as previously described.

L1—33b—32b—34b—2B1—2C—L2 (Fig. 4)

Contact 2C1 energizes coil SR

70 L1—47—46—2C1—SR—L2 (Fig. 4)

Contact 2C3 opens the circuit to clutch coil 27b stopping further movement of operator 43. Contact SR3 opens to deenergize coils 2A and 2B.

75 Contacts SR4 and SR5 transfer the operating cir-

cuit for coils 2Y and 1Y without effect at this time and these coils remain in the energized position. Contact 2B1 opens to deenergize coil 2C.

As the car continues upward plate 3d enters inductor IE opening contact EI without effect, as it is paralleled at this time by closed contact X5. Plate 3c then enters, opening contact E2 and interrupting the circuit to coil I (Fig. 4 previously traced). Contact I3 closes to short coil 1Y through a circuit starting at the left-hand side of coil 1Y (Fig. 4) that may be traced as follows.

Coil 1Y—1Y1—2Y1—SR4—1P6—I3—2Y4—15
coil 1Y (Fig. 4)

Relay 1Y drops to the deenergized position opening the shorting circuit by opening its contact 1Y1. Coil 2Y is held energized.

L1—2Y—2Y1—SR4—1P6—I3—2Y4—L2 (Fig. 4) 20

Contact 1Y3 in closing energizes coil 2G.

L1—H2—1Y3—1P12—3G3—2G—L2 (Fig. 4)

As the car progresses upwardly plate 3d leaves closing contact EI without effect. Plate 3d then leaves closing contact E2 which reenergizes coil I. Contact I3 in opening, opens the previously traced circuit to coil 2Y which then drops to the de-energized position, and contact 2Y5 opens the holding circuit to coil 3G which drops out. Resistor section 58d is inserted in the field of generator 54 reducing its voltage and slowing down motor 13a. During the interval between the final operation of relay 2Q which resulted in 35 energizing relay 3G to the time just mentioned where relay 3G drops out, the current in generator field 54a was building up to its final value and the elevator motor was accelerating to a speed suitable for a three floor run. 40

As the car progresses upward and as the platform passes floor 3, plate 3b enters inductor IF opening contact F1 deenergizing coil DR. Contact DR2 deenergizes coil I, closing contact I3 to close a pickup circuit to coil 1Y. 45

L1—2Y3—I3—1P6—SR4—2Y2—1Y—L2 (Fig. 4)

Contact 1Y2 energizes coil 1G.

L1—H2—1Y2—1P9—2G2—1G—L2 (Fig. 4) 50

With further motion of the car plate 3a enters inductor IF opening contact F2 deenergizing coil UR without effect. Plate 3b then leaves closing contact F1 energizing coil DR without effect, and finally plate 3a leaves closing contact F2 energizing coil UR and energizing coil I. Contact I3 opens and coil 2Y picks up. 55

L1—2Y—1Y1—1Y—L2 (Fig. 4)

Contact 2Y6 drops coil 2G by opening its self-holding circuit. 60

L1—H2—2Y6—2G4—2G—L2 (Fig. 4)

Resistor step 58e is now inserted in the generator field by opening of contact 2G1 (Fig. 3) 65 and motor 13a slows down further.

As the car progresses and its platform is midway between floors 3 and 4, plate 4d enters inductor IE opening contact EI without effect. 70 Then plate 4c enters opening contact E2, de-energizing coil I, and contact I3 deenergizes coil 1Y by placing a short on it. Contact 1Y3 energizes coil G.

L1—H2—1Y3—1P12—1G2—G—L2 (Fig. 4) 75

Plate 4d leaves, closing contact E1 without effect. Plate 4c leaves, closing contact E2 energizing coil I. Contact I3 in opening deenergizes coil 2Y. Contact 2Y5 opens the holding circuit to coil 1G which opens. Contact 1G1 inserts resistor 58f in the generator field circuit causing further slow down to the car's lowest operating speed. Contact 1G5 closes energizing coil O.

10 L1—1G5—2G3—3G2—4G2—5G2—6F4—O—L2
(Fig. 4)

As the car progresses and its platform nears floor 4, plate 4b enters inductor IF opening contact F1 which deenergizes coil DR deenergizing coil I. Contact I3 in closing energizes coil 1Y picking up the relay but without effect on the car. When the platform is very close to the floor plate 4a enters opening contact F2 deenergizing coil UR. As coil O is now energized, contact O1 is open and the opening of contact UR1 drops the holding circuit to coils U and M (Fig. 3), which now drop out opening the generator field circuit and applying the brake to stop the car at floor level. Contact M6 drops coil SR. Contact M8 drops coil 1P and when the car doors open, relay H opens and relay G is deenergized by contact H2 opening. The car is now at floor 4 with the doors open and the passenger who pressed the floor button can now enter the car to be carried to his destination.

The detailed sequence just described showed the car starting from the first floor accelerating for one one and one half floors of car travel, then retarding for one and one half floors to answer a call three floors distant from the starting point. A similar sequence can be traced for a four floor jump. In this case the car would accelerate one half floor more, an additional accelerating relay 4G would become energized and the retardation would require 2 floors.

Similarly for a five floor run, five accelerating steps to relay 5G would become effective and two and one half floors of acceleration and two and one half floor retardation would be required.

For a six floor run 6G relay would be required with three floors acceleration and three floors retardation. For longer runs, the car runs at its top speed for the additional floors and an operation of this type will be described.

It will be assumed for this example that the car is again at the first floor and that a call is registered for the ninth floor making an eight floor run. The sequence is as follows:

First floor to ninth floor run

55 In starting from the first floor the sequence of operation of the control mechanism is the same as for the shorter run up to the point where relay 1P picked up. In this case as segment 94 is not now energized coil 1P is not energized. The following relays and contactors are energized. W, H, U, M, 1Y, 2Y, 3G, DR, UR, I, 2A, 2B and 2C. Switch operator 43 has advanced to the second floor position and the car is accelerating between the first and second floor positions.

70 The sequence of relays 1Q and 2Q continues and relays 4G, 5G, and 6G are energized in sequence. Cross arm 41 is advanced one floor for each relay energized until the latter is positioned in the seventh floor position. Relays 4G and 5G have been deenergized and the following are energized at this time, W, H, U, M, 1A, 1B, 1C, 6G, DR, UR, I, 2A, 2B and 2C.

75 During the time required for this sequence the

car has advanced past the midpoint between the first and second floors and plate 2C cooperating with inductor IE and relay I has caused switch operator 43 to advance to the third floor position in a manner similar to its advance to the second floor position previously described. When relay 6G picked up it opened its contact 6G2 preventing further operation of relays 1Q and 2Q.

As the car advances accelerating to high speed it passes plates 2b and 2a which moves the switch operator 43 to its fourth floor position. Plates 3d and 3c move it to its fifth floor position. Plates 3b and 3a move it to its sixth floor position when the car is passing the third floor. When the car passes plates 4d and 4c midway between the third floor and the fourth floor switch operator is advanced to its seventh floor position. Cross arm 41 was left stopped at this position when relays 1Q and 2Q were made inoperative so that contact members 46 and 47 are now closed. In the sequence for moving operator 43 the last time relay 2C is energized and contact 2C1 energizes coil SR.

25 L1—47—46—2C1—SR—L2 (Fig. 4)

the relay locks in through a holding circuit.

L1—M6—SR1—SR—L2 (Fig. 4)

Contact SR5 in the operating circuit to coils 1Y and 2Y opens but without effect as relay 1C is energized at this time. Contact SR4 closes a similar circuit which is without effect as contact 1P6 has not closed yet.

The car continues towards the fourth floor position. Assume that a call is now registered at the ninth floor. Relay 9R becomes energized but without effect at this time except to energize a segment corresponding to the ninth floor to be engaged by brush 90 when the cross arm advances to the ninth floor position.

At the fourth floor position of the car plate 4b enters inductor IF opening contact F1 dropping relay DR and then relay I. Contact I1 in opening deenergizes coils 2A and 2B which in turn drops 2C. Contact I2 in opening (SR2 now being open) drops relays 1A and 1B which in turn drops relay 1C. When plate 4a leaves and contact F2 closes relay UR picks up reenergizing relay I. Contacts I1 and I2 close energizing relays 1A and 2A and clutch coils 27a and 27b simultaneously so that both cross arm 41 and operator 43 move to the eighth floor position.

Midway between floors 4 and 5, plates 5d and 5c enter inductor IE and open and close contacts E1 and E2 in sequence but without effect as contact 6G5 has closed shorting the terminals of contacts E1 and E2.

When the car arrives at the fifth floor, plate 5b opens contact F1, relay DR and relay I. Relays 2A, 2B, 2C, 1A, 1B and 1C are again deenergized by contacts I1 and I2 and when plate 5a leaves, relay I is reenergized and cross arm 41 and operator 43 move to the ninth floor position. When relays 1C and 2C pick up in the process of deenergizing the clutches 27a and 27b, a circuit is established to energize coil 1P.

L1—1P—1C4—2C4—90—ninth floor

segment of selector—SR2—L2 (Fig. 4)

and a holding circuit is established through contact 1P11.

The car now progresses, and when it passes the 6d and 6c plates midway between floors 5 and 6 contacts E1 and E2 again open and close without effect. When it approaches the sixth

floor, plate 6b opens contact F1 dropping DR and relay I. Contact I3 closes energizing relay 1Y.

L1—2Y3—I3—I6—SR4—2Y2—1Y—L2 (Fig. 4)

5 Coil 5G is energized by contact 1Y2.

L1—H2—1Y2—I9—6G6—5G—L2 (Fig. 4)

When plate 6a leaves the inductor, contact F2 closes energizing relays UR and I, opening contact 10 I3. Relay 2Y picks up, contact 2Y6 opens the holding circuit to coil 6G, and this relay drops out inserting resistor 58a in the generator field circuit to reduce the voltage of generator 54 and the speed of motor 13a.

15 Plates 7d and 7c pick up 4G and drop 5G which inserts resistor 58b.

Plates 7b and 7a pick up 3G and drop 4G which inserts resistor 58c.

20 Plates 8d and 8c pick up 2G and drop 3G which inserts resistor 58d.

Plates 8b and 8a pick up 1G and drop 2G which inserts resistor 58e.

Plates 9d and 9c pick up G and drop 1G which inserts 58f.

25 Relay 1G dropping picks up relay O. Relay 1Y is picked up as in the previous sequence.

Plate 9a enters inductor IF opening contact F2 dropping relay UR which drops relays U and M setting the brake and stopping the car in a manner similar to that described in the previously traced three floor run. The doors are 30 opened and the circuits are reset for another run.

From the foregoing descriptions, it will be evident that similar sequences can be traced 35 for any length of run. The rate of acceleration can be determined by the frequency of operation of relays 1Q and 2Q the point of slow down and the rate of retardation will be determined by the number of the accelerating steps and the travel 40 of the car. The steps may be individually adjusted by adjusting the values of the resistors 58a to 58f.

45 Provision has been made to enable the car operator to resynchronize the selector moving elements in the event that an emergency stop of the car should throw them out of proper position. The car will normally stop behind the position of cross arm 41. Assuming the car stopped at the third floor when the cross arm is at the fifth 50 floor, the position indicator circuit would illuminate lamp 5PI.

L1—5PI—65—60—M4—L2

The car operator presses button 19 (Fig. 3) 55 which will reverse two of the windings of three phase motor 23 that drives the clutch members in the selector thus reversing the motor 23. If button 20 (Fig. 4) is pressed, clutch 27a will be energized to cause movement of cross arm 41 in a reverse direction from normal motion and it will move one floor position. Indicator 4PI will then be illuminated. Operating button 20 again 60 will move the cross arm to the third floor position illuminating lamp 3PI, as this is the car's position, no further operation of button 20 is 65 required.

The switch operator 43 will also normally be in advance of the car's position. Operating button 21 (Fig. 4) while button 19 is pressed will 70 cause this member to move towards its third floor position, one floor at a time. When it reaches the third floor position lamp 18 (Fig. 4) will illuminate indicating to the operator the correct positioning of this element and the car 75 is again ready for normal service.

Operation from the car buttons is similar to that from hall buttons. Relay 2P picks up when movement of the cross arm causes brush 80 (Fig. 3) to engage an energized segment. Contact 2P1 closes a circuit to relay coil 1P in parallel with the circuit from any energized segment such as 94 as described. The car push buttons are provided with holding coils 1CBH to 5CBH which hold the associated buttons in the operated position until either contact W2 or X2 opens at the termination of the car travel in the associated direction.

10 Since changes may be made in the foregoing construction and different embodiments of the invention may be made without departing from the scope thereof, it is intended that all matter shown in the accompanying drawings and as set forth in the foregoing description shall be interpreted as illustrative and not in a limiting sense.

15 I claim as my invention:

20 1. In a control system for an elevator car operable past a plurality of floors; the combination of a start control, a motor for moving said car; starting and accelerating means responsive to said start control for starting said motor in a desired direction and accelerating it to any of a plurality of predetermined speeds; a stop control for each of the floors; retarding and stopping means responsive to operation of any one of said stop controls for causing said motor to stop 25 said car at the associated floor; selecting means comprising a first movable element and a plurality of stationary elements, there being one stationary element associated with each stop control, said first movable element being responsive 30 to actuations of said accelerating means for moving said element into engagement successively with said stationary elements, means responsive to engagement of said moving element with a stationary element associated with an operated 35 stop control for preventing further actuation of said accelerating means and for thereby stopping further motion of said first moving element; a second moving element responsive to movements of said car for causing said second element to 40 move in the same direction as said first moving element; means responsive to said second element moving into the same relative position as said first moving element for stopping further movement of said second element and for thereafter 45 causing actuations of said retarding means in accordance with movements of said car, means responsive to car movement into a position corresponding to that of said first and second moving elements to stop said motor and to thereby 50 stop said car at the floor corresponding to the actuated stop control.

55 2. In a control system for a car operable past a plurality of floors; a starting switch on said car, means responsive to an actuation of said starting switch for starting the car; automatic accelerating means for increasing the speed of the car in a plurality of steps; selecting means comprising a movable element operably engageable with a plurality of stationary elements one 60 for each floor; means responsive to said accelerating means for moving said movable element to successively engage said stationary elements one step for each accelerating step; a plurality of stop controls associated with said floors one for each 65 floor; and means responsive to operation of any one of said stop controls for conditioning the stationary element associated with said floor; means responsive to said movable element engaging a conditioned stationary element for 70 75

stopping further accelerating steps and thereby stopping further motion of said movable element; a second movable element operably cooperating with said first mentioned movable element; means responsive to car movement during acceleration of the car to move said second movable element into operable relationship with said first mentioned movable element; means responsive to said second element operably cooperating with said first element for preventing further acceleration of said car, for reversing the progression of said accelerating steps to thereby cause said car to retard, and for preventing further movement of said second movable element; said means responsive to car movement being also effective during retardation for progressively actuating said retardation steps; and means responsive to said car arriving at the floor associated with said operated stop control for stopping the car at said floor.

3. In a system for controlling the speed of an elevator car serving a plurality of floors, car actuating and stopping mechanism comprising means for accelerating said car to any one of a plurality of different speeds; means for retarding said car to its low speed preparatory to stopping; a switch on said car for operating said car actuating mechanism to start said car; a plurality of car control switches associated with said floors for operating said car stopping mechanism to stop said car; selecting means comprising a plurality of stationary elements one for each floor, a movable element cooperating with said stationary elements for controlling said accelerating means, and a second movable element for controlling said retarding means; said second movable element cooperating with said first mentioned movable element to stop further movement of said second movable element regardless of car movement; and means responsive to movement of the car for additionally controlling said retarding means.

4. In a system for controlling the starting, acceleration, retardation and stopping of an elevator car serving a plurality of floors the combination of a switch on the car; means responsive to operation of said switch for starting the car; means responsive to operation of said switch for accelerating the car to any of a plurality of operating speeds; a plurality of control devices, there being one associated with each floor served; selective means operable to a plurality of positions, there being a position corresponding to each floor, jointly responsive to said accelerating means and to an operated control device for determining the highest speed at which the car will operate; means operable in accordance with movements of the car and the position of said selective means for determining the end of the accelerating period for the car; means responsive to the cooperation of the last mentioned means with said selective means for stopping further operation of said last mentioned means regardless of further car motion; and means responsive to car movement for causing said accelerating means to retard said car to a low speed; and means for stopping said car from said low speed at the floor associated with said operated call device.

5. In a controller for an elevator car operable at a plurality of speeds, mechanism for accelerating the car comprising means for determining the distance through which the car is accelerated comprising, in combination, timing means operable at predetermined intervals; means operable

by said timing means for actuating said accelerating mechanism in a plurality of steps; movable means operable to a plurality of positions responsive to the operations of said timing means for successively moving said movable means through a plurality of positions; means for stopping the timing means and therefore the progression of said accelerating mechanism and the movement of said movable element; a second movable element operable to a plurality of positions responsive to movements of the car for successively moving said second movable element through a plurality of positions; means responsive to the movement of both elements through the same number of positions for ending the zone in which acceleration of said car in response to the accelerating mechanism takes place.

6. In a mechanism for controlling the acceleration and retardation of an elevator car started by the operation of a starting circuit and stopped in response to the operation of stop switches at the floors, the combination of means for accelerating and retarding the speed of the car; selecting mechanism comprising a stationary member, contact members supported thereon, there being at least one for each intermediate floor served by said car; a moving member operable to a plurality of positions, there being a position correspondent to each intermediate floor served; a contact member carried by said moving member cooperating with said stationary contact members and means responsive to said moving member cooperating with one of said stationary members for determining the extent of acceleration produced by said accelerating means, a second movable member cooperating with said first mentioned movable member and means responsive to the cooperation of said movable members for determining when retardation of said car shall start and for stopping further movement of said second movable member regardless of further car movement.

7. In a selecting mechanism for causing an elevator car to stop automatically at a floor in response to a registered floor call, the combination of a stationary element comprising a plurality of contact members, there being one associated with each intermediate floor served by said car; a first movable element movable to a plurality of positions, there being one position associated with each intermediate floor, said movable member carrying a contact member engageable with said stationary members; a second movable element independent of the movements of said first movable element; and a circuit operating device operable by the relative positions of said first and said second movable elements for stopping further movement of said movable elements and for simultaneously terminating acceleration and initiating retardation.

8. In a mechanism for controlling the movement of an elevator car operable past a plurality of floors the combination of mechanism operable to a plurality of positions corresponding to the floors served by said elevator; means for causing movement of said mechanism to each of said positions; a second mechanism also operable to a plurality of positions corresponding to the floors served by said elevator; means responsive to movements of said car for causing movement of said second mechanism to each of said positions; and means responsive to said first and second mechanisms assuming a predetermined position with respect to each other for rendering said second means ineffective to cause further

movement of said second mechanism in response to further movements of said car.

9. In a system for controlling the movements of an elevator car past a plurality of floors being served by said car, the combination of a starting switch and means responsive to operation of said switch for starting the car; a timing mechanism and means responsive to said timing mechanism to progressively accelerate said car to a plurality of low speeds and a high speed, a selecting device comprising a stationary member having a plurality of positions each corresponding to one of the floors being served, a first moving member operable to each of the positions, a second moving member operable to each of the positions, means responsive to said timing mechanism to move said first moving member from an initial position corresponding to the car's position forward in the direction corresponding to the car's direction of movement one position for each operation; a plurality of car control switches, one associated with each floor served and means responsive to said first moving member advancing to a position corresponding to a floor for which a control switch has been operated to stop further operation of said timing mechanism; means responsive to car movements for advancing said second moving member also from an initial position corresponding to said car's position forward in the direction corresponding to the direction of car movement, said second element advancing two positions for each floor distance traversed by the car; means responsive to said second element moving to its position corresponding to the floor for which said control switch was operated for causing said accelerating means to retard said car in a plurality of steps as said car advances until said car is operating at its lowest speed, and means responsive to further car movement to stop said car at the floor associated with said operated control switch.

10. In a system for controlling the movements of an elevator car past a plurality of floors being served by said car, the combination of a starting switch and means responsive to operation of said

switch for starting the car; a timing mechanism and means responsive to said timing mechanism to progressively accelerate said car to a plurality of low speeds and a high speed, a selecting device comprising a stationary member having a plurality of positions each corresponding to one of the floors being served, a first moving member operable to each of the positions, a second moving member operable to each of the positions, means responsive to said timing mechanism to move said first moving member from an initial position corresponding to the car's position forward in the direction corresponding to the car's direction of movement one position for each operation; a plurality of car control switches, one associated with each floor served and means responsive to said first moving member advancing to a position corresponding to a floor for which a control switch has been operated to stop further operation of said timing mechanism; means responsive to car movements for advancing said second moving member also from an initial position corresponding to said car's position forward in the direction corresponding to the direction of car movement, said second element advancing two positions for each floor distance traversed by the car; means responsive to said second element moving to its position corresponding to the floor for which said control switch was operated for causing said means to accelerate said car to act to retard said car in a plurality of steps as said car advances until said car is operating at its lowest speed, and means responsive to further car movement to stop said car at the floor associated with said operated control switch, and in the event that said accelerating mechanism accelerates said car to its highest speed means responsive to said accelerating means reaching the highest speed position for stopping further operation of said timing mechanism, and for causing said means responsive to car movement to move both moving elements substantially in synchronism with movements of the car.

WILLIAM F. EAMES.
